UNITED STATES PATENT OFFICE.

G. F. HERRICK, OF SHARON, MINNESOTA, ASSIGNOR TO HIMSELF AND
CHARLES SHEFFLER, OF SAME PLACE.

IMPROVEMENT IN FUNNELS.

Specification forming part of Letters Patent No. 43,075, dated June 7, 1864.

To all whom it may concern:

Be it known that I, G. F. HERRICK, of Sharon, in the county of Le Sueur and State of Minnesota, have invented a new and useful Improvement in Funnel; and I do hereby declare that the following is a full, clear, and exact description of the same, reference being had to the accompanying drawings, forming a part of this specification, in which—

Figure 1 represents a longitudinal vertical section of my invention. Fig. 2 is a plan or top view of the same.

Similar letters of reference in both views indicate corresponding parts.

This invention consists in the application of a packing of india-rubber or other soft and elastic material to the nozzle of a funnel, in combination with a vent-pipe extending down through the nozzle and connecting with a cork or valve, in such a manner that when the nozzle is inserted into the neck of a bottle or other vessel an air-tight joint is produced between the circumference of said nozzle and the inner surface of the neck, and in pouring liquid the air escaping from the vessel finds its way out through the vent-pipe, and when the vessel is full that quantity of liquid remaining in the funnel can be easily removed by closing the mouth of the nozzle by means of the cork or valve.

To enable those skilled in the art to fully understand and construct my invention, I will proceed to describe it.

A represents a funnel made of tinned sheet-iron or other suitable material in the usual form and manner. The nozzle B of this funnel is inclosed in a packing, C, of india-rubber or other soft and elastic material, so that when said nozzle is introduced in the neck of a bottle or other vessel an air-tight joint is formed between the inner and the outer circumference of the nozzle.

In pouring liquid through the funnel into

the vessel the air contained in the latter escapes through the vent-pipe D, which extends through the bridge-piece E, secured in the interior of the funnel and the lower end of which passes through a cork or cone valve, F, forming a flange, a, which supports the cork, as clearly shown in Fig. 1. A ferrule, b, surrounds the lower end of the cork, and this ferrule projects beyond the flange a of the vent-pipe to prevent the liquid from closing up the opening of said vent-pipe and allowing the air to escape freely from the vessel. The upper portion of the cork is beveled off to fit the mouth of the nozzle, and it is protected by a disk of tinned sheet metal or other suitable material. On pouring some liquid through the funnel into the bottle or other vessel the cork or valve F is opened, as clearly shown in Fig. 1 of the drawings, and the liquid descends around said valve, as indicated by black arrows, while the air in escaping from said vessel ascends through the vent-pipe, as indicated by red arrows. If the vessel is full, the surplus liquid remains in the funnel. Not a drop is allowed to escape between the nozzle and the neck of the bottle or other vessel, and in order to remove the funnel with the surplus liquid contained in it the valve is raised so as to close the mouth of the nozzle, and the funnel can be taken out of the neck of the vessel without danger of spilling any portion of the liquid.

What I claim as my invention, and desire to secure by Letters Patent, is—

The arrangement of elastic packing C with the nozzle of a funnel, A, in combination with the vent-pipe D and valve F, constructed and operating in the manner and for the purpose substantially as herein shown and described.

G. F. HERRICK.
